UNITED STATES PATENT OFFICE.

DON D. MILES, JR., OF SAN FRANCISCO, CALIFORNIA, ASSIGNOR TO BENJAMIN GOODWIN, OF SAN FRANCISCO, CALIFORNIA.

CONVERTIBLE MOTOR AND PUMP.

1,149,851.

Specification of Letters Patent. Patented Aug. 10, 1915.

Application filed September 6, 1912. Serial No. 718,886.

To all whom it may concern:

Be it known that I, DON D. MILES, Jr., a citizen of the United States, residing in the city and county of San Francisco and State of California, have invented certain new and useful Improvements in Convertible Motors and Pumps, of which the following is a specification.

The present invention relates to an improved automatic starter for engines and for all machinery where an initial impulse is necessary to start the apparatus before it is capable of being operated by its usual source of power, but is more particularly adapted to be employed in connection with internal combustion engines as applied to automobiles, and to a type wherein air under compression is employed to actuate an air operated motor and automatically thrown into operative relation, a connection between the motor and engine to be started; the motor after starting the engine being converted into a compressor, recharges the air in the supply reservoir and is then disconnected from the engine until it is again desired to start the engine.

The invention has for one of its objects to provide an improved device of the above character constructed with oscillating valves adapted to operate in a cylindrical barrel, piston barrels mounted in said valves and arranged to adjust the valves to compensate for the wear in said barrel.

A further object of the invention is to provide a valve and piston barrel so arranged that the valve will be forced into its seat on each compression stroke of the piston in its barrel.

Other and important objects are to provide a motor which after starting the engine may be readily converted into a pump for recharging the air supply tank, without altering or changing any part of the starting motor, but by simply changing the direction of the flow of air current within the motor and to provide a device which is light in weight, simple in construction, and thoroughly efficient in all of its operations.

With these and other objects in view, the invention consists in the novel combination of parts hereinafter fully described, illustrated in the accompanying drawings, forming a part of this application and pointed out in the claims hereto appended; it being understood that various changes in the form,

proportion, size, and minor details of construction within the scope of the claims may be resorted to without departing from the spirit or sacrificing any of the advantages of the invention.

To comprehend the invention reference should be had to the accompanying sheets of drawings, disclosing one form of my invention wherein—

Figure 1 is a side elevation of my starting engine, disclosing the casings for the oscillating valves, the engine crank shaft, the piston rods connected thereto, and the valve and operating means for converting the engine into a compressor, the valve being in the position when the device is used as a compressor. Fig. 2 is a side elevation of Fig. 1, disclosing the connection between the starting engine crank shaft and the drive shaft of the engine, one of the oscillating valves in which is mounted the piston cylinder, the connection from the air storage tank, the mechanism for operating the clutch on the engine shaft, and one of the piston rods connected to the starting engine crank shaft. Fig. 3 is a vertical sectional view taken on line 3—3—Fig. 1, disclosing one of the oscillating valves, and the mounting for the same, the piston cylinder mounted therein, the valve controlled passages in the base of the motor and in the casing for the oscillating valves, for converting the starting engine into a compressor, and the mechanism for automatically operating the connection between the starting engine and the engine shaft to be started. Fig. 4 is a sectional view on line 4—4—Fig. 1, disclosing the construction of the oscillating valves and the manner of mounting the piston cylinders therein, the valve controlled passages in the casing for the oscillating valves, and one of the pistons mounted in the cylinders. Fig. 5 is a vertical sectional view of the preferred clutch, and the manner of mounting the same on the engine crank shaft. Fig. 6 is a detail view of the rotary valve in the position when the invention is used as a motor to start the engine. Fig. 7 is a view in detail of the rotary valve removed from the engine.

Referring more particularly to the drawings, the numeral 1 designates a suitable base provided at each end with journals 2, in which are mounted to rotate a shaft 3, provided adjacent each end with crank arms 110

4, preferably arranged at an angle of 90 degrees about the shaft and to which are attached the lower ends of piston rods 5, which carry at their upper ends pistons 6, 5 mounted to reciprocate in suitable cylinders 7, the cylinders each being mounted centrally of annular disk shaped valves 8, adapted to oscillate in a suitable annular casing 9 which encircles the valves and 10 which extends upwardly from the base 1. The valves 8 are divided transversely into upper and lower sections 10 and 11, which are retained together by suitable screws 12, extending through suitable smooth bores in 15 the members 10 and are threaded at their lower ends in the member 11, and the valves are secured in position by the retaining rings 13, secured to each end of the casing 9.

The piston cylinders 7 are screw threaded 20 at their upper ends into the members 10 and are received in their lower ends in seats in the members 11, and it will be observed that by rotating the cylinders that the members 10 and 11 may be adjusted in the casing 9 to compensate for any wear that may have taken place in the oscillation of the valves.

The valves 8 are provided respectively at their upper and lower surfaces with ports 30 14 and 15 which communicate with the interior of the cylinders 7, one on either side of the piston 6, the port 14 is adapted on the oscillation of the valve to alternately register with ports 16 and 17 communicating 35 respectively with the upper ends of inlet and exhaust channels 18 and 19 provided in the annular casing 9 and port 15 is adapted to alternately register with ports 20 and 21 communicating respectively with the lower 40 ends at the inlet and exhaust channels 18 and 19. The channels 18 and 19 communicate at their lower ends through the respective ports 18' and 19' with the corresponding channel associated with the opposite oscillating valve and from the connecting ports 18' and 19' extend the downwardly inclined ports 18² and 19². The ports 17 and 21 of the exhaust channel 19 are normally closed by spring seated ball valves 17' and 21' positioned in and opening into the channel 19 and said valves are unseated on each compression stroke of the pistons 6.

The channel 18 communicates with the outside atmosphere through an inlet opening 22, adapted to be normally closed by a spring seated inwardly opening valve 23, the stem 24 of which extends centrally within a lubricating cup 25, the lower end of which is provided with openings 26 at the sides thereof and is screw-threaded in the inlet opening 22.

The motor base 1 is provided with a horizontally extending inlet port 27, one end of which communicates with an air supply reservoir 28, the normal capacity of which is

approximately 150 pounds, and the other end of which communicates through a vertically extending port 29 with the port 18², and the motor base 1 is also provided with a horizontally extending exhaust port 30 70 communicating at one end with the atmosphere and terminating at its opposite end in a vertical passage 31, which communicates with the lower end of the exhaust port 19².

Provided in the base 1 above the ports 27 and 30 is a suitable tapering opening 32 in which is mounted to rotate a tapering valve 33, the same intersecting the communication between the exhaust port 19² and the port 31 and the port 18² and the port 29, and said valve is retained in position by the nuts 34, the valve is disclosed in Fig. 3 of the drawings, when the device is used as a compressor for recharging the air reservoir. The valve is provided at its large end with a longitudinally extending tapered chamber 35 closed at its enlarged end by the cap 36, and communicating at its smaller end with one end of a longitudinally extending bore 37 which communicates at its other end through a small 90 opening 38 with a longitudinally extending bore 39, the end of which is adapted to be closed by a screw plug 40, and said opening 38 is adapted to be closed by an inwardly opening ball valve 41 normally seated by a coil spring 42, the tension of which is regulated by the screw plug 40. The communication between the chamber 35 and the bore 37 is controlled by a tapered valve 43 opening

into the chamber 35, and normally seated 100 by a coiled spring 44 which surrounds a spindle 45 extending centrally of the chamber 35 and which is carried by the cap 36. Formed in the surface of the valve 43 to communicate with the interior of the tapered chamber 35 and arranged at diametrically opposite sides of the valve surface, are cut out portions or openings 46 and 47, the opening 47 being slightly larger than the opening 46 and the openings adapted when the valve is rotated in the position, as in Fig. 6, to make a direct communication from the air supply reservoir 28 and the inlet port 18² and when the valve is rotated so that the openings are positioned, as in Fig. 3, the opening 46 will not register with the port 18², but owing to the larger size of the opening 47, it will continue to register with the communication from the air reservoir 28, the check valve 43 preventing the escape of 120 air from the channel 35 into the channel 37. The surface of the valve is also provided adjacent the bore 37 with a cut out portion or opening 48, arranged approximately at right angles to the openings 46 and 47, and 125 said opening 48 is of a size approximately one-half the diameter of the valve.

In the operation of the valve, the opening 48 provides a communication between the exhaust port 19² and exhaust port 30, 130

when the openings 46 and 47 permit of a direct communication between the air supply reservoir 28 and the inlet port 18², as in Fig. 6, and the device is operated as a 5 starter. When the valve is positioned, as in Fig. 3, the communication between the exhaust port 19² and the exhaust port 30 leading to the atmosphere is cut off, and the 10 communication between the inlet port 18² and the air reservoir is also cut off, and the device is operated as a compressor for recharging the pressure in the tank 28, the air is drawn in through valve controlled inlet opening 22, and forced through the exhaust 15 channel 19, into the channel 37 unseating the valve 43 from whence it is forced through the opening 47 recharging the pressure in the tank 28.

Communicating with the tapering opening 32 are the upper ends of channels 49 and 50, the channel 49 adapted, when the valve 33 is in the position disclosed in Fig. 6, to register with a bore 51 formed in the surface of the valve 33 and communicating with the 20 interior of the chamber 35, and the channel 50 adapted when the valve is in the position disclosed in Fig. 3, and the device is operating as a compressor, to register with a bore 52 formed in the surface of the valve 33 and communicating with the bore 39 adjacent the ball valve 41, controlling the opening 38 leading thereto. The lower ends of the channels 49 and 50 communicate respectively with the opposite ends of a chamber 35 25 53, formed in the base 1 below the shaft 3 and said bore extends parallel to said shaft.

Mounted to reciprocate in the chamber 53 is a piston rod 54, provided midway of its length with a piston 55 carrying oppositely 30 disposed flexible packing rings 56, and the ends of said piston rod are adapted to operate through stuffing boxes 57, which close the opposite ends of the chamber 53.

Any suitable connection between the motor and the engine to be started may be 35 employed, the form disclosed in the drawings being merely for illustration.

Keyed to one end of the shaft 3 is a toothed sprocket 59, around which extends 40 a chain 60, the other end of which extends around a sprocket 61 loosely mounted on the crank shaft 62 of the engine. One face of the sprocket 61 is provided with an annular cone shaped projection 63, which is 45 adapted to be thrown into engagement with an overhanging flange 64, on the periphery of a disk 65 keyed to the crank shaft of the engine; the sprocket 61 and the disk 65 being normally forced apart by the action 50 of coiled springs 66 positioned between the same.

The mechanism for throwing the two clutch members into engagement comprises a lever 67 having an enlarged head portion 55 which fits loosely around the shaft 62 adja-

cent the hub of the sprocket 61, and is provided with a flat face adapted to contact with the hub of the sprocket 61 and the opposite face of the head is provided with a cam surface 68, which, when the clutch members are separated lies in a cam groove formed in a ring 69, loosely surrounding the shaft 62 and the ring being secured to any stationary support. The free end of the lever 67 is pivotally connected by a rod 70 with the end 71 of the piston 54.

The mechanism for operating the valve 33 consists of a lever 72, secured midway of its length over the end of the valve 33 and the upper end of said lever is pivotally connected by a link 73 to a pivotally mounted foot pedal 74, positioned within convenient reach of the vehicle operator, the lever being normally thrown in the dotted line position A, in Fig. 1 of the drawings, by the 80 action of a coiled spring 75. The lower end of the lever 72 is provided with a curved arm 76, which is adapted to contact with the end of the piston rod 54 after the lever has been thrown into the position B, Fig. 3, to position the valve to start the engine and the connection between the motor and engine has been thrown into operation, the arm remaining in contact with the piston as long as the motor is operating as a compressor to recharge the air supply reservoir 28. Upon the reservoir being recharged to its capacity, the piston rod 54 will be moved inwardly in disengagement from the arm 76 and the lever 72 will be drawn by the action of the 90 spring 75 to the position A, in Fig. 1, at which time the solid portions of the valve 33 will close the communication leading from the air supply reservoir 28 to prevent the escape of air therefrom.

The operation of my improved starter is as follows:—Assuming that the lever 72 is in the position A, Fig. 1, and it is desired to start the engine, the operator presses the foot pedal 74 which throws the lever 72 into the position B—Fig. 1, at which time the lever in its movement will rotate the valve 33 into the position shown in Fig. 6; and when the valve is in this position, the ports 46 and 47 will be so positioned as to permit a direct communication from the air supply reservoir 28 to the inlet port 18². The air as it enters the channel is under high pressure and the same enters the cylinders 7 through the port in the oscillating valve 8, that is in register with the inlet channel, the air as it enters forces the pistons to the opposite ends of the cylinders, and the air in front of the pistons is forced out through valve controlled ports into the exhaust channel 19 from where it is forced through the cut out 48 in the valve 33, to the atmosphere, the cut out 48 providing a communication from the exhaust port 19² to the port 30, when the communication is open between the air sup-

ply reservoir and the intake channel 18. Simultaneously with the above operation the port 51 of the valve 33 will aline with the channel 49, and a portion of the air admitted from the tank 28 will enter the channel 53 and force the piston therein into the position, as shown in Fig. 3, at which time the clutch controlling the connection between the motor and engine will be thrown into engagement, and the engine crank shaft 62 will be rotated to start the engine.

After the engine has been started, the operator releases pressure on the foot pedal 74 and the spring controlling the same will move the lever 72 into the position disclosed in Fig. 1, and the lower end 76 of the lever will contact with the end of the piston rod 54. When in this position the valve 33 has been rotated to a position to convert the motor into a compressor operated by the engine it has just started, and the communication from the air supply reservoir to the inlet channel 18 has been cut off as has the communication from the exhaust channel to the atmosphere. On the suction strokes of the pistons air is drawn into the piston cylinders through the valve controlled inlet port 22, and is forced on the compression stroke of the pistons through the valve controlled ports leading into the exhaust port 19². The air under compression is forced from the exhaust channel 19 through the opening 48 in the valve 33 into the bore 37, the pressure of the air therein unseating the valve 43, and flowing into the channel 35 from where it flows through the opening 47 into the channel leading to the air supply reservoir for recharging the pressure therein. When the pressure in the tank 28 reaches its capacity the air compressed by the pistons will flow from the chamber 37 through the opening 38 unseating the valve 41 controlling the same, and will be forced through the opening 52 in the valve, which is now alined with the channel 50 and the air under compression will enter the chamber 53 and force the piston 55 carried by the piston rod 54 to the opposite end of the chamber from that shown in Fig. 3, which will throw out the clutch and disconnect the connection from the compressor to the motor. The piston rod 54 in its movement in the channel will disconnect from the lower end 76 of the lever 72, and the action of the spring 75 will move the lever into the position A, in Fig. 1, at which time the valve 33 will be rotated to a position which will close the communication from the air reservoir to the inlet channel and the port 19² of the exhaust channel will be closed.

It will be observed that by providing an oscillating valve constructed in two parts, mounting the same in an annular casing and securing the piston cylinder therein, as here-

tofore described, that the piston on the compression stroke thereof will tightly seat in the casing, that portion of the oscillating valve which is located in the direction of the travel of the piston, and that leakage of air around the valve is thus prevented.

Having thus described my invention what I claim is—

1. A motor comprising a ported oscillating valve formed in sections, an annular shell surrounding said valve, piston cylinders mounted within said valve and communicating with the ports therein, pistons slidably mounted in said cylinders, a drive shaft, a connection between said pistons and drive shaft, a power shaft, a connection between said drive and power shafts, a reservoir for fluid under pressure, a controlled inlet communication between said reservoir and said oscillating valves to admit air into said cylinders to operate the pistons therein, and an exhaust communication between said oscillating valves and the outside atmosphere.

2. A motor comprising a ported oscillating annular valve formed in sections, an annular shell surrounding said valve, a piston cylinder mounted within said valve and connecting opposite sections thereof, an adjustable connection between said piston cylinder and said valve sections whereby said cylinder is capable of adjustment to expand the sections of said valve to seat in said shell, a piston in said cylinder, a drive shaft connected to said piston, a reservoir for fluid under pressure, and a controlled inlet and exhaust communication between said reservoir and said valve.

3. A motor comprising an annular shell provided with intake and exhaust channels within its body, a pair of disk valves each formed of two semi-circular sections and mounted to oscillate in said shell, piston cylinders mounted within said valves and adapted to be adjusted to seat said semi-circular sections in said shell, said valves provided with ports in their peripheral edges adapted to communicate with the interior of said piston cylinders, and with said intake and exhaust channels in said shell, pistons mounted in said cylinders, a drive shaft, a connection between said pistons and drive shaft, a power shaft, a connection between said drive shaft and power shaft, a reservoir for fluid under pressure, and valve controlled connection between the cylinders and the fluid storage reservoir.

4. A motor comprising an annular sectional shell provided with intake and exhaust channels within its body, a pair of disk valves each formed of two semi-circular sections and mounted to oscillate in said shell, piston cylinders mounted within said valves, adjustable connections between said cylinders and said sections to seat said semi-

circular sections in said shell, said valves provided with ports in their peripheral edges adapted to communicate with the interior of said piston cylinders, and with said intake 5 and exhaust channels in said shell, pistons mounted in said cylinders, a drive shaft, a connection between said pistons and drive shaft, a power shaft, a connection between said drive shaft and power shaft, a reservoir 10 for fluid under pressure, and valve con-

trolled connections between said reservoir and said cylinders and said exhaust channels.

In testimony whereof I have signed my name to this specification in the presence of two subscribing witnesses.
